UNITED STATES PATENT OFFICE.

PAUL ALEXANDER DUMRAESE, OF MILFORD, CONNECTICUT.

CARBURETOR.

Application filed September 19, 1921. Serial No. 501,628.

To all whom it may concern:

Be it known that I, PAUL A. DUMRAESE, a citizen of the United States, and a resident of Milford, in the county of New Haven and State of Connecticut, have invented a new and Improved Carburetor, of which the following is a full, clear, and exact description.

This invention relates to carburetors and has for an object to provide an improved construction wherein the quantity of air is automatically controlled by the action of the suction of the engine.

Another object is to provide a carburetor in which a conical-shaped air controlled member is provided which gradually opens as the suction increases.

A further object of the invention is to provide a carburetor in which the fuel and air are thoroughly commingled before leaving the carburetor.

An additional object is to provide a carburetor in which none of the parts may be adjusted except the needle for increasing and decreasing the fuel opening.

In the accompanying drawing—

Figure 1 is a top plan view of the carburetor disclosing one embodiment of the invention.

Figure 2 is a vertical section through Figure 1 approximately on line 2—2.

Figure 3 is a detail bottom plan view of a sleeve embodying certain features of the invention.

Figure 4 is a plan view of a controlling cone embodying certain features of the invention.

Referring to the accompanying drawing by numerals, 1 indicates a float chamber which may be of any desired kind and connected with the casing 2 by a suitable connecting pipe 3. The casing 2 is provided with a butterfly valve 4 of any usual or preferred construction and controlled in the usual manner.

In forming the casing 2 a body section 5 is provided of a certain diameter, a neck section 6 of a smaller diameter and an end section 7 which presents an opening or throat 8 for receiving the butterfly valve 4 and which also presents an annular shoulder 9 against which the spring 10 presses. The spring 10 also presses against the end 11 of cone 12. The cone 12 is provided with a sleeve or tubular section adjacent the end 11 and a conical-shaped sec-

tion at the opposite end, said conical section having a bearing portion 13 adapted to engage the sleeve 14 at the point that the cone section 15 merges into the tubular section 16. This connection is a sliding connection so that the tubular section 16 may slide a short distance within the sleeve 14 and the seat 13 rest against a tapering conical-shaped bore 17 of sleeve 14. This bore merges into an annular opening 18 which in turn merges into an inlet cone-shaped opening 19 whereby the sleeve 14 will act as a choker or venturi. As shown in the drawing the cone 12 has been unseated somewhat but not completely pulled out of the sleeve 14.

It will be noted that the conical-shaped bore 17 does not extend to the end of the sleeve 14 but falls short thereof whereby the end section 20 acts as an annular ring but is divided into small projections or fingers by the longitudinal grooves 21. By reason of this construction, when the cone 12 is unseated somewhat as shown in Figure 2, air may pass through the passageways 21 and from thence through the various openings 22 in the cone 12 and finally out with the fuel through the throat 8. It will be noted that the cone 12 has an entrance opening 23 of slightly less diameter than the opening 18. When the carburetor is standing still and there is no suction thereon, the cone section 15 will be fitting snugly against the bore 17 and the principal opening for the passage of fuel and air will be through the opening 23 though a small quantity of air may pass through the passageway 21 and around the outside of the sleeve section 16.

The sleeve 14 is provided with bores 24 and 25 which register with suitable openings in the casing 2 whereby the needle valve 26 may freely operate in the bore 24 and the jet or nozzle 27 may be positioned in the bore 25. The pipe 3 is connected with the jet 27 so as to supply fuel thereto while the needle valve 26 regulates the amount of fuel regardless of the opening provided. It will be noted that the fuel will be discharged substantially centrally of the passage-way or opening 18 and, consequently, will be drawn through opening 23 and finally into the engine. At the same time, air will be drawn through opening 18 and the various passage-ways 21. As the section increases the cone 12 will be gradual-

ly moved against the action of spring 10 so as to provide a greater and greater opening for the air passing through the opening 18 and the passage-ways 21. The provision 5 of the various openings 22 in the cone 12 also causes a better mixing and commingling of the fuel and air before the combined air and fuel pass out as substantially a gas through the throat 8.

10 When the engine is first started, the mixture will be much richer than after it has attained some speed as the amount of air in proportion to the fuel will be less as most of the air from the passage-way 21 has 15 been shut off. As the engine speeds up and, consequently, does not need as rich a mixture, the air will increase by reason of the opening of the passage-ways 21 and also by moving the opening 23 further from opening 18. It is, of course, evident that more 20 gas could be provided in the usual way by operating the needle valve 26 which is connected with the accelerator pedal. When starting in cold weather, a rich mixture is 25 desirable and, consequently, a valve or a chocking member 28 is provided which is

in the nature of a butterfly valve and it is connected with a suitable controlling lever 29. This lever may have a rod or other member extend to the dashboard or some 30 other convenient place so as to be operated at any time.

What I claim is:—

A carburetor, comprising a casing, a venturi positioned in the casing formed with a 35 tapering bore merging into a cylindrical inner slotted end, the slots in said slotted end merging into passage-ways extending to the opposite end of the venturi, a cone coacting with said venturi formed with a 40 foraminous tapering section adapted to engage the walls of said tapering bore, a solid cylindrical section normally fitting into said cylindrical inner end and closing said slots, and a central bore extending entirely 45 through the cone, a spring for normally holding the cone so that the tapering section is engaging the walls of said tapering bore, and means for supplying fuel to the point of smallest diameter of the venturi.

PAUL ALEXANDER DUMRAESE.
